US0D1015780S

(12) **United States Design Patent** (10) **Patent No.:** **US D1,015,780 S**
(45) **Date of Patent:** **** Feb. 27, 2024**

(54) **TABLE**

- (71) Applicant: **Seville Classics Inc.**, Torrance, CA (US)
- (72) Inventors: **Wayne Calco**, Torrance, CA (US); **Martin Carillo Avila**, Santa Clarita, CA (US)
- (73) Assignee: **Seville Classics, Inc.**, Torrance, CA (US)
- (**) Term: **15 Years**
- (21) Appl. No.: **29/800,314**
- (22) Filed: **Jul. 20, 2021**
- (51) LOC (14) Cl. **06-03**
- (52) U.S. Cl. **USPC D6/656.16**
- (58) **Field of Classification Search**
USPC D6/406.1, 406.2, 641, 642, 655, 655.18, D6/655.19, 655.21, 656, 656.13, 656.14, D6/656.15, 656.16, 656.17, 656.18, D6/656.19, 686, 691, 691.4, 708, 708.16, D6/708.22
CPC A47B 13/00; A47B 21/00; A47B 21/314; A47B 2021/0364; A47B 23/00; A47B 23/001; A47B 2021/0307

(57) **CLAIM**

The ornamental design for a table, as shown and described.

DESCRIPTION

FIG. 1 is a perspective view of a table showing our new design.

FIG. 2 is a front view thereof.

FIG. 3 is a rear view thereof.

FIG. 4 is a left view thereof.

FIG. 5 is a right view thereof.

FIG. 6 is a top view thereof.

FIG. 7 is a bottom view thereof.

FIG. 8 is a perspective view of a table according to another embodiment; and,

FIG. 9 is a front view of FIG. 8.

The features shown in broken lines in the figures do not represent claimed subject matter. The cutaway symbols shown in broken lines depict a symbolic break in length and form no part of the claim. The appearance of any portion of the article between the break lines forms no part of the claim.

1 Claim, 9 Drawing Sheets
